CLAIM

The ornamental design for a pair of jars with blackout sleeves for a sprouting kit, as shown and described.

DESCRIPTION

FIG. 1 is a front side perspective view of a pair of jars with blackout sleeves for a sprouting kit in accordance with the present design;

FIG. 2 is a front elevation view thereof;

FIG. 3 is a left side elevation view thereof, the right side elevation view being a mirror image thereof; and,

FIG. 4 is a top view thereof.

The broken lines around the necks and the base of the blackout sleeves surrounding the pair of jars illustrate stitching, which form no part of the claimed design. The broken lines in the center of the lids illustrate mesh, which form no part of the claimed design.

Any shading and cross-hatching are not features of the design but are utilized to illustrate the surface contours of the pair of jars with blackout sleeves for a sprouting kit design in the drawings.
